VARDELL, EXECUTRIX, OF DALLAS, TEXAS.

DOFFING MECHANISM FOR GINS.

1,426,689.

Specification of Letters Patent. Patented Aug. 22, 1922.

Original application filed August 22, 1919, Serial No. 319,105. Divided and this application filed December 9, 1920. Serial No. 429,562.

To all whom it may concern:

Be it known that ARTHUR A. VARDELL, deceased, late a citizen of the United States, and resident of Dallas, in the county of Dallas and State of Texas, did invent new and useful Improvements in Doffing Mechanism for Gins, of which the following is a specification.

This invention relates to gins of the saw type, and more particularly to means for doffing the separated fibre from the fibre-separating instrument.

All the saw gins as heretofore constructed deliver a great volume of air as an incident 10 of the construction and operation of the doffing brush forming an essential part of the gin. This air, charged with fine particles of lint and dust, when delivered into the room, menaces the health and efficiency 15 of the operators, and constitutes a serious 20 fire risk. Attempts have been made to minimize these risks by connecting the individual gins to deliver into a common conveyor, or by air-doffing the saws by separately generated 25 blast or suction currents, or by other expedients, none of which are wholly successful for this purpose.

In the best practice known in the prior art, pneumatic doffing, or the common collection 30 of fibre by delivery into a common flue or conveyor has resulted in unnecessary expenditure of power, often amounting to four or more horse-power per gin. The rotating elements of the gin itself expend 35 much power in moving with them a great volume of air.

When external pneumatic means heretofore have been employed the air-moving effort of the elements of the gin has been 40 retained, with resultant waste of effort.

Principal objects of this invention are to provide doffing means for gins or linters adapted to operate with less power than heretofore required; to reduce the volume of 45 air moved by the doffer; to effect improved separation from the saws of a saw gin of fibres, and to provide a brush doffer of improved construction and mode of operation for these purposes which shall be durable 50 and efficient.

In the accompanying drawings, in which the invention is illustrated by way of example by one preferred construction only,

Figure 1 is a vertical detail section of a

gin comprising a brush doffer according to 55 the invention and illustrating one disposition of parts cooperating with the new doffer; and

Figure 2 is a longitudinal section of the 60 doffer brush.

In the preferred form of the device there is illustrated one instance of a new genus of saw gins in which an improved relation of the doffer brush to the saws, based upon observation of a mode of operation of such 65 brushes not heretofore subscribed to by those skilled in the art is utilized to improve both the working conditions of gin-neries and the economy of the recovery of fibre. It has heretofore been believed that the 70 air-current set up by the rotating gin brush employed to doff the useful fibre from the saw cylinders is essential to the function of the brush as a doffer. It has also been believed that a relatively slight interengagement of the brush with the space between the individual saws of the saw cylinder 75 was the best arrangement, and the losses of fibre heretofore observed due to the return of useful fibre into the seed cotton or between the bars of the grate, thence to pass 80 out through the seed-gate, have been accepted as inevitable. In the present gin a deeper engagement than usual of the brush with the saw is employed, a much smaller 85 brush than usual is preferred, and the function of the brush to move a current of air, while utilized, is no longer exclusively relied upon to create such air currents as are needed in the gin, the brush being designed 90 to have as little function as a fan as possible, the conveying movements within the gin being controlled by suction currents exteriorly 95 created.

Therefore, in one aspect the invention is directed to the reduction of the volume of air moved by the gin brush, heretofore thought to be unavoidable and heretofore permitted to create in the surroundings of the gin a bad condition due to escape of air 100 laden with fibre and with dust blown out of the gin by the operation of its elements. The present gin not only recovers all of the fibre but avoids the pollution of the air of the place in which it is installed by the device of inducing inward currents of air into 105 the machine and its connections at all points where it is open to the air of the room, the

only air-current leaving the gin being a suction current conveying away the relatively pure lint in a closed flue. This current is of very greatly less volume than the 5 air-current blown away from the gin in the ordinary operation, and may be of correspondingly higher velocity and be carried by a smaller flue, operating to convey the fibre with less consumption of power than is required by the usual arrangement of gin parts working as a fan and blowing a larger 10 volume of air at a lower velocity away from the gin.

It is not herein claimed broadly the new 15 combination of gin parts for the purposes shown, described and claimed in said parent application Serial No. 319,105, filed August 22, 1919, from which the present subject-matter has been divided on the requirement 20 of the Patent Office.

Referring to the drawings, the machine frame as usual may comprise uprights 1, side panels, and wooden or metal longitudinal struts, etc., the end frames comprising 25 the uprights 1 and transverse members having thereon bearings for a saw shaft 2 having if desired adjustments permitting the shaft 2 to be raised or moved as wear and recutting of the saw-cylinder made up of 30 shaft 2 and saws 10 reduces the diameter of the cylinder, which may be driven as usual.

A doffer brush 5 rotating with a driven shaft 3 on bearings presently to be mentioned, is so arranged as to bring the shaft 35 3 beneath and but little behind the vertical from the center of saw-cylinder 2, so that contact of the saws 10 with the brush 5 occurs near (or much nearer than usual to) 40 the bottom of the saw-cylinder, for purposes which will presently appear.

The disposition of the brush with respect to the saw cylinder enables the centrifugal throw of the saw cylinder, by which the motes and heavy impurities are thrown off, 45 to be utilized to separate these motes from the fibre clinging to the saws.

The preferred arrangement is such, as 50 more fully explained in said parent application, to permit the bearings for shaft 3 of the brush, a concave 37 near the brush, the front end 65 of a suction conduit, and the rear end of a housing plate 70 all to be adjusted vertically together by moving supports 40 for the brush-shaft bearings and 55 for these parts. Such adjustment controls the extent of engagement of the doffer brush with the saws 10.

Instead of the brush as usual being arranged to have a fanning action by being built up of longitudinal rows of bristles, the brush 5 may be solid, or (as shown in Fig. 2) consist of annular rows of bristles, each row having tufts arranged to engage at each side face of each saw.

65 Referring to Fig. 2, the brush 5 may con-

sist of separator disks 5^a of hard fibre, wood or metal, strung on an enlargement 3^a of shaft 3 threaded at 3^b to receive compression nuts 5^b, the disks 5^a having therein turned grooves 5^c to receive annular brush-tuft strips 5^d, which are cemented or otherwise fastened together, and between which the radial tufts 5^e are held. The brush-strips may be thin rings of fibre, metal or paper, and the thickness of the separator disks 70 75 may, as shown, be the distance between the saws 10, or a divisor of this distance. In the latter case, there are rows of tufts between the saws, available for use by shifting the shaft 3 endwise. To prevent the 80 brush-strips turning in their seats, the fastening means may include axially extending pegs, pins or tubular rivets spaced to take into bores formed in the bottoms of the grooves 5^c. In the preferred form 85 shown the pins 5^f are fastened in one face of each disk 5^a and extend through perforations in the brush strips into engagement with the bores in the next disk.

The axially narrow tufts 5^e run in line 90 with the saws 10, some of their bristles wiping each side of the saw. The whole diameter of the brush may be, and preferably is, much less than in usual practice. Such a brush may be rotated at the usual 95 speeds of from 1000 to 1200 R. P. M. without blowing a strong air current thereby.

For adjustment purposes the brush is mounted in bearings, not shown, carried by and vertically adjustable on vertical slides 100 40 in ways on the frame.

The surroundings of the brush 5 are completed by an adjustable front housing plate 70 and end plates 72, pivoted at 71 to lugs on the plates 40 and held in place by 105 vertically adjustable stops 73. The front section of the housing may be lowered for access to the brush, and to adjust the space 74 into which the doffer-brush centrifugally throws the lint into the air flowing 110 into the lint-trunk 50.

The operation of the machine will now be apparent. The saw cylinder, running at any desired speed, usually about 550 R. P. M., takes the lint into its teeth when pulling it 115 from its attachments at the grate, or carries it with the saws and near them either by travel in the air moving by friction with the saws, or by electrical attraction. The brush operates to doff the fibre thus carried 120 by the saws 10 exclusively or predominantly by mechanically sweeping the sides and peripheries of the saws, the peripheral speed of the brush exceeding that of the saws to a substantial degree. The only air moving 125 with the brush is that frictionally engaged by its surface and tufts, and upon the sector of the brush approaching the saws and lying within casing 37 there is no air-inlet, so that the slight vacuum induced by 130

the brush in this space is filled up from chamber 28, above and behind the saws and brush, if from anywhere; on the sector of the brush following engagement with the saws, the suction air-current into trunk 50 exceeds the effort of the brush to fan a current of air.

The action of the tufts of the brush on the lint to be doffed is thus purely mechanical and results in clearing more deeply than heretofore the space between the saws of the lint traveling in this space, and throwing off centrifugally all of the lint affected by the brush into the space 74 at and within 15 the suction-passage leading into trunk 50.

When the saws, or the brush, or both, are worn by use, the shaft 3 may be adjusted with respect to the concave 37 to maintain the relation of the brush to the concave, and 20 the slides 40 lifted to position the trunk 50, the plate 70, the concave 37, and the brush 5 properly in relation to the new diameters of saw, or brush, or both. The useful life of a brush is greatly increased by this 25 vision, and by providing reserve circles of tufts between each pair of saws, as above mentioned, the life of the assembled brush may be doubled.

What is claimed is:

30 1. The combination with a suction gin of a doffer brush comprising a peripherally imperforate cylinder having axially spaced, annular series of bristles secured thereto.

2. In combination with a gin saw, a doffer 35 brush comprising an isolated and substantially uninterrupted axially narrow circumferential row of brush tufts arranged substantially in the plane of said saw, the parts being so constructed and arranged that the 40 edge of the saw cuts deeply into the row of bristles.

3. In combination with a saw cylinder comprising a series of saws, a doffer brush comprising a peripherally imperforate cylinder having a series of axially spaced annular rows of brush bristles so constructed and 45 arranged as respectively to lie opposite corresponding saws.

4. In combination with a gin saw cylinder, a doffer brush comprising an imperforate cylinder provided with tufts arranged in unbroken, axially spaced, annular series, whereby to minimize air resistance to rotation of the brush.

5. In combination with a gin saw cylinder, 55 a doffer brush comprising internally annularly grooved spacer disks, annular brush strips having projecting tufts seated in said grooves, and means for holding said parts in assembled relation on a shaft.

6. In combination with a series of gin saws, a doffer brush comprising a peripherally imperforate cylinder provided with a number of axially narrow and unbroken peripheral circles of brush tufts, and means 65 adapted to position and rotate each circle of tufts in engagement with the periphery of and a peripheral portion of each face of each gin-saw to be doffed.

7. A gin brush comprising a pair of spacing and supporting disks strung upon a shaft, said disks having annular recesses in their proximate faces, a brush strip seated within the space formed by the combined recesses, said brush strip consisting of a pair 75 of connected annular rings having brush bristles interposed therebetween, and adjustable means for pressing said disks into intimate contact.

8. A gin brush comprising a shaft, a plurality of rigid disks strung thereon, each of said disks having annular recesses in its opposite faces, an annular brush strip seated in the spaces formed by opposed recesses in adjacent disks of said brush strips, each consisting of a flexible supporting element having a row of bristles secured thereto, axially disposed pins for retaining said strips in fixed position in the respective spaces, and means for retaining said disks upon the 90 shafts.

9. In a gin of the kind having therein a saw cylinder having a series of spaced saws, the combination with the saws of a doffer brush cylinder comprising a shaft, a series 95 of annular brush-strips having an unbroken series of brush-tufts thereon, removable means for holding the brush-strips in assembled relation on the shaft, one annular brush corresponding to the position of each 100 saw, and means for rotating the saw and doffer brush respectively in this relation.

Signed by me at Dallas, Texas, this 4th day of December 1920.

HIGHLAND GEE VARDELL,
*Executrix under the last will and testament
of Arthur A. Vardell, deceased.*
